UNITED STATES PATENT OFFICE.

KINYON W. MANWARING, OF DE WITT, IOWA.

COLTER ATTACHMENT.

SPECIFICATION forming part of Letters Patent No. 231,074, dated August 10, 1880.

Application filed March 6, 1880. (No model.)

To all whom it may concern:

Be it known that I, KINYON W. MANWARING, of De Witt, Clinton county, and State of Iowa, have invented a new and useful Improvement in Plow-Colter Attachments, of which the following is a specification.

My invention relates to the attachment of the yoke-shaft of a plow-colter to a suitable clamping device employed to fix the colter to the plow-beam; and the devices employed, their construction, application, and mode of action will be hereinafter more fully explained.

In the accompanying drawings, Figure 1 is an isometrical representation of a colter attachment embodying my invention in place on a portion of a plow-beam, and at Fig. 2 is represented a vertical central section in the lengthwise direction of the plow-beam.

In the figures, *a* represents a portion of a plow-beam, on which, in connection with a suitable clamping device, my improved attachment is mounted. The clamping-frame in this instance is substantially the same as the frame patented to me September 30, 1879, No. 220,161; and it consists of plates *b*, suitably separated and relatively fixed in such separated position by transverse bars *c*, *d*, and *e*, and are also perforated, as at *f*, to receive screw clamping-bolts *h*, which, in connection with a clamping-plate, *i*, serve to fix the clamping-frame in an adjustable manner to the plow-beam.

The outer edges of the transverse bars *c* are corrugated in the lengthwise direction of the clamping-plates, as shown in the drawings; and the connecting-bars *d* are placed to form a transverse slot to receive a clamping-bolt employed to fix in place thereto in an adjustable manner a suitable socket to receive the shaft of the colter-yoke.

At *k* is represented a colter-shaft socket fitted with arms *l*, having their end portions corrugated to engage the corrugations in the transverse bars. This colter-shaft socket is provided with a center arm, *m*, provided with a center opening to receive a clamping-bolt, *n*, which is passed into position in the arm through a suitable opening, *o*, in the outer surface of the socket, and when in place in the frame, in connection with a suitable screw-nut, serves to hold the socket to the clamping-frame in such a manner that it may be readily adjusted laterally to properly align the colter with the plow; and it is capable of a

vertical inclination laterally to properly adjust the colter with the plow, which is accomplished by inclining either end of the socket to or from the plow-beam, or at an angle to the vertical center thereof. This socket is provided with a boss, *p*, at or near its ends, which are each fitted with a set-screw, *s*, which operate against a plate or bar, *s'*, placed in a key-seat-like groove, *s''*, formed in the socket immediately under the set-screws. This socket receives the journal-shaft *t* of the colter-yoke freely in such a manner that it may be adjusted vertically to regulate the running depth of the colter supported in the yoke, and may be adjusted on its axis to align the colter to the line of the forward movement of the plow, and when adjusted is firmly held in position by the clamping force of the set-screws.

At *u* is represented a colter of the usual form, made from the material usually employed in such work, and is mounted to revolve between the yoke-arms in bearings formed in their lower ends, substantially in the usual manner.

By this construction and arrangement I am enabled to produce, at a small cost, a reliable rigid colter (known as such in the trade) capable of all the required adjustments to render it a practical article of its kind.

I am aware that a tubular socket has been provided with a set-screw for retaining the yoke-shaft in any desired vertical adjustment, and I make no claim to such construction, as my invention relates to the peculiar construction and combination of parts described, and pointed out in the claim.

I claim as my invention—

The combination, with the clamping-frame, a colter-shaft socket provided with continuous tubular bearings at its upper and lower ends, and a fastening-bolt which is inserted through an opening in the socket, the head of the bolt being seated in a recess formed on the inner surface of said socket, of a clamping-plate inserted between the colter-shaft and socket, and clamping set-screws inserted in the socket and adapted to secure the colter-shaft in any desired vertical adjustment, substantially as set forth.

KINYON W. MANWARING.
